UNITED STATES PATENT OFFICE.

HARRY S. READ, OF NEW HAVEN, CONNECTICUT, ASSIGNOR TO WESTERN ELECTRIC COMPANY, INCORPORATED, OF NEW YORK, N. Y., A CORPORATION OF NEW YORK.

VACUUM-TUBE CIRCUITS.

Application filed March 17, 1920. Serial No. 366,640.

To all whom it may concern:

Be it known that I, HARRY S. READ, a citizen of the United States, residing at New Haven, in the county of New Haven, State of Connecticut, have invented certain new and useful Improvements in Vacuum-Tube Circuits, of which the following is a full, clear, concise, and exact description.

This invention relates to vacuum tube circuits, and more particularly it relates to the multi-stage amplifier circuits.

As is well-known in the art, weak currents or signals may be amplified to any desired degree by impressing them on one or more vacuum tube amplifiers arranged to work into each other by suitable circuit connections. In employing a vacuum tube as an amplifier it has been found that the tube works most efficiently when the impedance between the control electrode and the cathode is composed substantially of resistance with no capacity component. In that form of a vacuum tube where the control electrode is within the tube and adjacent to the cathode, there is present a certain amount of capacity between the cathode and the control electrode dependent in value upon the size and the distances between the three electrodes and the electrical constants of the associated circuits. The displacement current resulting from this capacity effect is appreciable even for currents of low frequencies, but if the frequencies impressed are relatively high, such as 50,000 or more, the displacement currents are of sufficient strength to cause a certain amount of distortion in the current waves to be repeated.

In accordance with this invention this capacity effect between the control electrode and the cathode of a vacuum tube is substantially neutralized by inserting in series with the control electrode and the cathode an impedance such as an inductance of such a value as to be resonant with the effective capacity for the frequency or band of frequencies which are of the most importance in the impressed currents. With such an arrangement the inductance will neutralize the capacity effect so that for the incoming currents the impedance between the control electrode and the cathode will be substantially all resistance, thereby eliminating the undesired distortion in the repeated wave.

This invention will be better understood by reference to the following detailed de-

scription taken in connection with the accompanying drawing which illustrates this invention as applied to a two-stage amplifier.

Referring to the drawing, 3 and 4 are vacuum tube amplifiers which are designed to amplify currents from line 5 and impress them upon an outgoing line 6. A conventional source 24 of current waves to be repeated is shown connected to line 5. 60 Although the frequency or frequencies impressed on line 5 may be of any desired value, this invention is preferably employed in cases where the most important frequencies to be repeated are ultra audio frequencies. Tubes 3 and 4 contain respectively cathodes 7 and 8, anodes 9 and 10, and grid or control electrodes 11 and 12. Heating current for cathode 7 is supplied by battery 13, while cathode 8 is heated by 65 a battery 14. Space current for the two tubes is supplied from the two sources of voltage 15 and 16. Tube 3 is connected in the incoming line by means of a transformer 17. The currents impressed on the 70 secondary of transformer 17 are impressed upon the terminals of a high resistance 18, and consequently change the potential on control electrode 11, so as to produce corresponding changes in the output current of 75 tube 3. The variations in the output current of tube 3 are impressed across the terminals of a high resistance 19 upon the grid of tube 4, thereby causing tube 4 to amplify the current waves still further before they 80 are impressed on the outgoing line 6 by means of transformer 20. In order to prevent the capacity effect which may be present between control electrode 11 and cathode 7 from distorting the incoming waves, inductance 21 is added in series with these electrodes and with one side of the incoming line. This inductance 21 should be of such a value as to be resonant with the grid cathode effective capacity for the frequency 85 or band of frequencies that are of importance in the incoming waves. With such an arrangement this undesired capacity is neutralized and the impedance between the grid and the cathode for the incoming currents 90 consists substantially entirely of resistance. In a similar manner, the capacity between grid 12 and cathode 8 may be neutralized by an inductance 22 of such a value as to be resonant with the grid cathode effective 95 100 105 110

capacity for the important incoming frequency or band of frequencies.

As an example of the value inductance 22 may have, it was found that with a vacuum 5 tube having an effective capacity 200 mmf. between its input electrodes for a frequency of 50,000 cycles, the inductance should be approximately five millihenrys.

It is to be understood that this invention 10 may be variously modified from the above disclosure without departing in any wise from the spirit of this invention as defined in the appended claims.

What is claimed is:

- 15 1. In a wave amplifying system for amplifying a band of frequencies, an electric discharge device having an anode, a cathode and a control electrode, the impedance between said cathode and control electrode comprising a capacity component, means for impressing signals of a band of frequencies upon said control electrode, said capacity effect between said electrodes causing certain frequencies of said band to be transmitted 25 with less efficiency than other frequencies of said band, and means for rendering the transmission efficiency of said system more nearly uniform for all the frequencies in said band, comprising an inductance element connected directly in series with said first mentioned means, said control electrode, and said cathode, and forming a series resonant circuit with the capacity between said control electrode and said cathode to improve 35 the efficiency for those frequencies at which the system would otherwise have relatively low efficiency, while still permitting the efficient transmission of those frequencies of the band for which the system without said inductance has high transmission 40 efficiency.
2. In a wave amplifying system for amplifying a band of frequencies, an amplifier having an anode, a cathode and a control 45 electrode, a transformer having a secondary winding, a circuit including said secondary

winding, said control electrode and said cathode in series, said control electrode and said cathode having an appreciable capacity effect therebetween which causes said amplifier to transmit certain frequencies of said band with greater efficiency than other frequencies of said band, and an inductance connected directly in series in said circuit, 50 which inductance, while remaining in a constant adjustment, so resonates at a constant frequency with said capacity effect as to increase the efficiency, at those frequencies at which the amplifier alone has relatively low efficiency, to such a value that the width of 55 the band of frequencies which the system is capable of transmitting with equal efficiency is increased.

3. In a wave amplifying system for amplifying a band of frequencies, an amplifier 60 having input electrodes between which a capacity effect exists whereby said amplifier has a tendency to transmit certain frequencies of said band with greater efficiency than other frequencies of said band, a transformer 65 having a secondary winding, a circuit including said secondary winding and said input electrodes in series, and means for rendering the transmission efficiency of said system more nearly uniform for all the frequencies in said band, comprising an inductance connected directly in series in said circuit, 70 which inductance, while permitting said amplifier to transmit with substantially the same efficiency those frequencies of the band for which it has high transmission efficiency, and with the same adjustment of the circuit, resonates with the capacity effect between said input electrodes to improve 75 the efficiency for those frequencies at which the amplifier alone has relatively low efficiency.

In witness whereof, I hereunto subscribe my name this 12th day of March, A. D., 1920.

HARRY S. READ.
